UNITED STATES PATENT OFFICE.

CHARLES A. KETTERER, OF EAST ST. LOUIS, ILLINOIS.

REFRIGERATOR.

Application filed August 9, 1920, Serial No. 402,175. Renewed February 1, 1923.

To all whom it may concern:

Be it known that I, CHARLES A. KETTERER, a citizen of the United States, and resident of East St. Louis, in the county 5 of St. Clair and State of Illinois, have invented certain new and useful Improvements in Refrigerators, of which the following is a specification containing full, clear, and exact description, references being 10 had to the accompanying drawings, forming a part thereof.

My invention relates to improvements in refrigerators and has for its object a refrigerator wherein the display or storage 15 chamber of a refrigerator is chilled and at the same time provided with a sufficient amount of moisture to keep articles contained therein in a salable condition.

A further object is to construct a refrigerator in which the display or storage chamber of a refrigerator can be supplied with either dry cold air or with a pre-determined amount of moisture. This moisture being desirable whenever articles containing juices 20 are stored therein, as the dry cold air will absorb the juices from the article if there is no moisture present in the air and cause shrinkage and considerable loss in weight, while if too much moisture is contained in 25 the air the articles stored within the chamber absorb this moisture and become soft and flabby and unfit for sale.

In the drawings:

Fig. 1 is a longitudinal sectional view of 35 a refrigerator containing the apparatus made use of in my method.

Fig. 2 is a top plan view of one of the central air circulating pipes.

Fig. 3 is an enlarged sectional view showing blocks or plugs made use of to assist in regulating the amount of moisture supplied to the air.

Fig. 4 is a top plan view of the lid used on the ice receptacle showing the dampers 45 made use of for regulating the flow of air through the ice receptacle and through the side air tubes.

Fig. 5 is a cross sectional view taken on the line 5—5 of Fig. 1, and showing the 50 arrangement of the refrigerator coil in the liquid container.

Fig. 6 is a perspective view of one of the blocks or plugs made use of.

In the construction of my device I make 55 use of the refrigerator 7, which is provided with a storage or display chamber 8

and a refrigerating chamber 9. These chambers are separated from each other by means of the splash apron 10, which is composed of two horizontal members with spaced 60 apart vertical slats extending across, and secured on each side of the horizontal members, and so arranged that the slat on one side will close the space beneath two adjacent slats on the other. This permits a free 65 circulation of air through the splash apron, but at the same time prevents any liquid from splashing therethrough, and into the display chamber, which is located along the bottom of the refrigerator, the reticulated 70 wall 11 and the deflector 12; the splash apron, reticulated wall and deflector serving a two-fold purpose, the first being to prevent articles in the storage or display chamber from falling into the refrigerating 75 chamber, and second, the splash apron and reticulated wall 11 allowing the entrance of cold air into the display chamber while the deflector 12 causes the warm air to rise upwardly and enter the refrigerating 80 chamber through the passage 13 formed between it and the top of the refrigerator from whence it passes over the refrigerating means. The refrigerating means is constructed in the following manner: 85

In the bottom of the refrigerating chamber 9 is placed a drip pan 14, which is provided with the usual outlet 15 for removing waste water from the chamber 9. Resting within the pan 14 are angle 90 irons 16, secured to these angle irons is a liquid container 17. This liquid container has two of its sides 18 sloping, while the sides 20^a are vertical. These sloping sides are secured to the bottom 19. Secured to 95 the bottom and extending upwardly therethrough to a plane even with the top edge of the liquid container are large air pipes 20. Extending thru these air pipes at a distance from the top edge thereof is a rod 100 or rivet 21, and on this rod or rivet rest pipes 22 and 23. These pipes are arranged concentric with the pipe 20 and are held in this position by means of the corrugated tubes or pipes 24 and 25, the pipe 22 having 105 its upper edge terminating at a short distance above the edge of the pipe 20, and the pipe 23 terminating at a short distance above the upper edge of the pipe 22. Within the pipe 22 and at a short distance below its top is an X 26, which is formed of two rivets or wires crossing each other at right 110

2
angles extending diametrically across the pipe and on this rests a washer or reticulated plate 27, the purpose of which is to prevent foreign substances from entering the pipe 22 and lodging on the rod or rivet 21 and causing foul air in the pipe. Secured through the sloping bottom 18 are the pipes 28 which have their upper ends terminating on a plane with the upper edge of the liquid container. These pipes are provided with a bar or rivet 29 on which rest the pipes or tubes 30 and 31, the pipes 30 terminating at a short distance above the upper edge of the pipes 28, while the pipes 31 extend upwardly through the ice container 32 and contact with the underside of the cover or lid 33 of the ice container. This cover or lid is provided with a plurality of openings 34, these openings terminating in downwardly projecting lips 35. The holes are so arranged as to be vertically opposite the pipes 23 and 31 and the lips 35 of the openings 34 of the outside pair of openings are designed to enter the tubes or pipes 31. Over the openings 34 are placed dampers 36. These dampers are pivotally mounted on the lid at a point indicated by the numeral 37 and are provided with an up-turned portion 38 to permit the moving of the same. These dampers are provided with a series of graduated openings 39 so that the amount of air entering the ice receptacle 32 or the pipes 31 can be regulated, or closed off entirely. The ice receptacle 32 is composed of sheet metal walls 40, which are secured to the outside of the angle irons 16, while the liquid receptacle 17 is secured to the inner faces. The lower edge of the ice receptacle terminates on a line with the upper edge of the liquid receptacle. This leaves a passageway 41 extending completely around the two receptacles, with the exception of the four corners where it is closed by the angle irons. Secured to the angle irons and at a short distance above the lower edge of the ice receptacle are angle irons 42, these angle irons acting as a support for a sheet of reticulated material 43 which acts as a bottom for the ice receptacle. Within the liquid container 17 is secured a coil 44, and through this coil a refrigerant such as ammonia, or the like, is designed to be passed. The refrigerating coil 44 is submerged in a liquid which has been chemically treated so as to prevent its freezing. This liquid completely fills the chamber 17 and in order to supply a continuous amount of fresh non-freezing liquid to the container 17 a quantity of crushed ice is placed on the reticulated bottom 43. Mixed with this ice is a chemical such as salt, which, when mixed with the melted ice, will form a non-freezing solution or liquid. This liquid constantly drip-

ping into the container 17 will cause it to overflow and run over the sides of the container, and also enter the pipes 20 and 28. This overflow will prevent frost from accumulating on the container or in the pipes, and the result will be a cold air without excess moisture. The pipes 22 and 30, as well as the corrugated pipes 23 and 24 are supplied with this non-freezing mixture by the liquid which drops into them through the bottom of the ice container. When it is desired to allow frost to accumulate on the outside of the liquid container 17 I make use of a plurality of L-shaped blocks or plugs 45. A portion of these plugs is adapted to enter the opening 41 formed between the walls of the ice chamber and the walls of the liquid container and prevent the overflow of non-freezing liquid at that point. The method of insertion of these plugs is clearly illustrated in Fig. 3. These plugs are formed of various lengths so that the entire opening 41 may be closed if found desirable, or only certain portions of this opening may be closed. The operation of my refrigerator is as follows:

The first step is to fill the liquid container 17 to the top with a non-freezing liquid, which is preferably water treated with a chemical such as salt or the like, so as to render it non-freezing, the ice container 32 is then filled with cracked ice with which is mixed some kind of chemical as is mixed with the water, the refrigerant is then turned on so that it may circulate through the coil 44 and the dampers 36 are regulated so as to allow the passage of air through the ice in the ice container and through the tubes 31. As the ice in the ice container melts it dissolves a certain portion of the salt mixed therewith and the result is a non-freezing solution, which drops through the reticulated bottom 43 of the ice container and into the liquid container 17, which it will overflow as well as the pipes 20 and 28. In addition to this a certain portion of the liquid dripping from the ice container will enter the pipes 22, 23 and 30. This will cut off frost which has gathered on the inside of the pipes while the overflow of the container 17 will cut off the frost from the sides of the container. When it is desired to supply only a small amount of moisture to the refrigerator, the dampers over the pipes 31 are closed and the only air admitted will be through the ice chamber. This air must pass through the ice chamber before passing through the tubes 20 and 28 and consequently will absorb a slight amount of moisture. If it is desired to feed only dry air the dampers 36 over the pipes 31 are opened and the dampers admitting air to the ice chamber closed. This will allow a direct circulation through the tubes 28 and 31

while practically no circulation will take place through the tubes 20, 22, 23 and 30. By opening the valves over the ice chamber in addition to the valves over the tubes 31 a mixture of moist and dry air is obtained, and in order to obtain more moisture in the refrigerator the blocks or plugs 45 are made use of, closing up a portion or all of the opening 41. Then, when this opening is entirely closed, the only outlet for the overflow of the liquid container 17 is through the pipes 20 and 28 and the frost will be permitted to form on the outside of the container 17, and when this frost has reached a certain thickness no more frost will form, and the balance of the moisture in the air will be chilled and condensed into a fog which will moisten the food stuffs in the display chamber, and cause sogginess and mildew.

I may also, if desired, place a humidity gauge in the storage or display chamber so that the amount of humidity can be ascertained readily and the refrigerating compartment and its contents be so regulated as to supply more or less moisture, as is required.

As shown in Fig. 1 the arrows indicate the flow or circulation of air, the cold air entering at the bottom of the display or storage chamber and leaving it at the top through the passage 13. In the event that all of the dampers 36 are closed no circulation will take place through the pipes in the ice and liquid chambers, and the only chilling done will be by the contacting of the air with the outer surfaces of these chambers. Thus it is also possible to regulate the amount of cold air delivered to the storage chamber, as well as the moisture, since the air when contacting only with the outside of these containers will not chill as readily, nor as thoroughly, as when permitted to pass through the tubes, and consequently the display or storage chamber will not become as cold as when the dampers 36 are open, as then a more rapid circulation of air takes place.

After serving its purpose in removing the frost the overflow from the liquid container 17 drips into the pan 14 and then passes through the pipe 15 either into a sewer or into some suitable receptacle.

I do not desire to be limited to the exact construction shown, as it can be used with equally good results in large storage chambers or in refrigerator cars, and I may also, if desired, eliminate the coil 44 and use only the ice in the ice chamber. But, the mode of operation and results accomplished will be the same, with the only exception that by using the coil 44 it is possible to obtain a lower degree of temperature within the storage or display chamber than by the use of ice only.

Having fully described my invention what I claim is:

1. A refrigerator comprising a storage chamber, a refrigerator chamber communicating therewith, a drip pan located in said refrigerating chamber, a liquid container supported in said refrigerating chamber above said drip pan, an ice container supported above said liquid container and spaced apart therefrom, a perforated lid for said ice container, dampers having graduated openings pivotally secured to said lid for regulating the size of perforation, and plugs for closing predetermined portions of the space between the liquid container and ice chamber.

2. A refrigerator comprising a storage chamber, a refrigerating chamber in communication therewith, a drip pan located in said ice chamber, a liquid container supported in said refrigerating chamber above said drip pan, an ice container having a reticulated bottom supported above said container and spaced apart therefrom, air circulating pipes located in the liquid container, some of which terminate below the ice chamber and some extending therethrough, a perforated lid for the ice chamber, some of said perforations registering with the air pipes extending through the ice chamber, dampers for regulating the flow of air through said air pipes, dampers for regulating the flow of air through said ice chamber, and plugs for closing predetermined portions of the space between the liquid container and ice chamber.

In testimony whereof, I have signed my name to this specification.

CHARLES A. KETTERER.
